UNITED STATES PATENT OFFICE

2,181,339

EASY OPENING CAN

Paul E. Pearson, Chicago, Ill., assignor to Continental Can Company, Inc., New York, N. Y., a corporation of New York

Application August 28, 1937, Serial No. 161,507

3 Claims. (Cl. 220—54)

The invention relates generally to the tear strip cans wherein are provided weakened tear strips terminating in tongues adapted to be engaged by keys and wound about said keys for rupturing the can material along the lines defining the strips and thereby effecting an opening of said cans, and it primarily seeks to provide a novel form of such can made up from a minimum of body stock.

10 It is customary in this type of can to provide a key having a shank slotted to receive the extended tongue of a tear strip so as to afford a firm grip on said tongue and assure completion of the winding and tearing of the strip without 15 danger of the key slipping in the roll of torn strip stock. For this reason it is necessary that the tongue extensions be made quite long. In the blanking out of the can bodies a strip of metal must be cut away at the blank end at each 20 side of the tear strip portion in order to form the tongue extension, and it will be obvious that this waste of metal will be increased or diminished accordingly as the length of tongue extension is increased or diminished. The invention 25 seeks to provide a novel form of tear strip can in which a tongue extension of minimum length may be employed.

An object of the invention is to provide a novel 30 form of tear strip can structure in which the tongue extension is short in length and equipped with a key lug receiving recess or aperture.

Another object of the invention is to provide a novel form of tear strip can structure of the solder bonded seam type in which the tongue extension 35 is equipped with means for damming solder flow so as to assure against solder bonding of the free end of said extension to the can body.

Another object of the invention is to provide a novel key structure including a lug extension engageable in the tongue extension aperture or 40 recess.

With the above and other objects in view that will hereinafter appear, the nature of the invention will be more fully understood by reference to the following detailed description, the appended claims, and the several views illustrated in the accompanying drawing.

In the drawing:

Figure 1 is a side elevation of a can embodying the invention.

Figure 2 is a plan view.

Figure 3 is an enlarged face view of the can face bearing the tongue extension.

Figure 4 is a detail horizontal section taken 55 on the line 4—4 on Figure 3.

Figure 5 is a detail horizontal section taken on the line 5—5 on Figure 3.

Figures 6, 7 and 8 are detail vertical sections taken respectively on the lines 6—6, 7—7 and 8—8 on Figure 3.

Figure 9 is a side elevation of the shank portion of the key.

Figure 10 is a detail cross-section taken through the lug bearing portion of the key shank.

Figure 11 is a detail perspective view of the body blank edge portion in which the tongue extension is formed.

In the drawing I have illustrated the invention embodied in a can comprising a cylindrical body 5, formed in the usual manner by shaping a rectangular blank about a form and securing its ends in a side seam 6, and end closures or caps 7 applied in the conventional manner.

A tear strip 8 extends around the body and is 20 formed by defining score lines or weakened portions 9. One edge of the blank of which the body is formed is bent back upon itself at each side of the strip 8 as at 10, but at the position of the strip this edge is left extended to form a 25 key receiving tongue extension 11 (see Fig. 11). It will be observed by reference to Figs. 3 and 11 that the length of the tongue 11 is substantially the same as that of the bent seam portions 10 so that in the blank the edge which provides the 30 tongue constitutes a continuous or substantially continuous line, thus eliminating all wasting or cutting away of body stock.

The tongue 11 preferably is provided with a key receiving aperture or recess 12, and between 35 the aperture and the line of the seam 6 the tongue is equipped with a dam lug 13 which extends across a major portion of said tongue as shown in Figs. 3, 4, 7 and 8. A tongue accommodating depression 14 is formed in the can body and this 40 may be intentionally shaped during the formation of the can body or formed incidentally by the mere pressing down of the dam-lug-equipped tongue to the position indicated in Fig. 4.

As is well known, can side seams are solder 45 bonded as indicated at 15, in Figs. 4 and 5. This solder commonly is wiped onto the seam by a soldering roll rotatable about an axis disposed in parallelism with that of the can bodies, and the molten bonding material flows by capillary 50 attraction into the interstices of the seam.

Obviously, it would be undesirable to have the solder flow under the tongue extension 11 and cause it to become attached to the can body in the depression 14. Permanent freedom of the 55

tongue extension is assured by provision of the dam lug 13 which extends across beneath the tongue 11 as shown in Figs. 3 and 4 and effectually dams the capillary flow of solder toward 5 the free end of said tongue as indicated at 16 in Fig. 4.

A tear strip winding key is provided as shown at 17 in Fig. 2. This key includes a flattened head portion 18 preferably apertured to facilitate 10 temporary attachment thereof to the can top by a drop of solder as indicated at 19. The shank 20 of the key is pinched as at 21 to provide a lug extension 22 adapted to engage in the tongue aperture 12. By reason of the provision of the 15 lug 22 and the receiving aperture 12, a tongue extension 11 of minimum length can be employed without sacrificing efficiency of the key and tongue winding grip engagement, and slippage between these parts during winding of the tear 20 strip is avoided. It will be noted also that the rib or lug 13 spaces the tongue extension in the depression 14 so as to facilitate insertion of the key lug 22 into the aperture 12 of said extension.

In opening the improved can, the key 17 is removed 25 from its temporary attachment at 19 on the can top and the lug 22 thereof is inserted in the tongue aperture 12 with the key head projecting above the can top. By now turning the key, the tear strip 8 will be wound about the key 30 shank and the upper end of the can will be separated from the lower portion thereof.

In the foregoing description, I have disclosed a novel tear strip can in which body stock waste is eliminated without sacrificing efficiency in key 35 and tear strip cooperation, in which soldering down of the key receiving tongue is avoided, and in which application of the key is greatly facilitated.

I claim:

40 1. A sheet metal container comprising a body portion having its side edges joined and solder-bonded, said body having score lines encircling the same for forming a tearing strip, said body wall being extended in the region of the tearing strip for providing a tongue to which a key may 45 be attached for rupturing the metal along the

score lines, said tongue being integral with the outer lapping section of the side seam and said body wall adjacent the side seam being depressed to receive said tongue, said tongue in the region adjacent the side seam having an inwardly projecting rib forming a solder dam to prevent the soldering of the tongue to the body wall, and said tongue having an opening therethrough adjacent the rib to permit the attachment of the winding key thereto. 5

2. A sheet metal container comprising a body having the edge portions thereof shaped to provide interlocking hooks solder-bonded together to form a side seam, said body being provided with score lines forming a tearing strip, the inner hook in said side seam being continuous from the upper end of the seam to the lower end thereof and the outer hook terminating in the region of the tearing strip so that the tearing strip may have an integral tongue projecting therefrom, 20 the body wall adjacent the side seam being depressed to form a pocket for said tearing tongue, said tearing tongue having an inwardly extending rib lying along the side seam close to the edge of the inner hook for forming a dam to prevent 25 solder from passing beneath the tongue and securing the same to the body wall, said tongue having an opening therethrough adjacent the rib for attachment of the winding key to the tearing strip. 30

3. A sheet metal container comprising a body portion having its side edges joined and solder-bonded, said body having score lines encircling the same for forming a tearing strip, said body wall being extended in the region of the tearing strip for providing a tongue to which a key may 35 be attached for rupturing the metal along the score lines, said tongue being integral with the outer lapping section of the side seam and said body wall adjacent the side seam being depressed to receive said tongue, said tongue in the region adjacent the side seam having an inwardly projecting rib forming a solder dam to prevent the soldering of the tongue to the body wall. 40
